UNITED STATES PATENT OFFICE.

DENNIS FRISBIE AND EDWARD M. LOCKWOOD, OF PHILADELPHIA, PENNSYLVANIA, ASSIGNORS TO SAID DENNIS FRISBIE.

ELEVATOR.

SPECIFICATION forming part of Letters Patent No. 349,706, dated September 28, 1886.

Application filed February 18, 1886. Serial No. 192,332. (No model.)

To all whom it may concern:

Be it known that we, DENNIS FRISBIE and EDWARD M. LOCKWOOD, both of the city and county of Philadelphia, in the State of Pennsylvania, have invented a certain new and useful Improvement in Elevators for Carrying Passengers or Freight Up and Down in Buildings, of which the following is a specification.

The invention contributes to the safety, compactness, and economy of the mechanism.

We provide means whereby a brake is applied at each stoppage of the engine, and also means for insuring a slow motion of the brake-applying device, so that, whatever be the means employed, the brake cannot be applied so suddenly as to cause mischief. The several devices conduce to the safety of the operation. The mechanism is simple and reliable.

We provide an automatic stop mechanism by which, when the hoisting-rope is slackened from any cause, the power of the engine is applied to make changes, whereby the steam is shut off and a brake is applied. It sometimes happens that the car is accidentally arrested at some stage in its descent, so that the hoisting-rope is slackened, and on its release at some later period the car falls. This stop prevents such accidents by promptly stopping the unwinding the moment the rope is slackened. Our invention requires only a gentle weight or other force pressing against the hoisting-rope to determine its slackness, the power to effect the required change being derived not from such force directly, but from the power of the engine, the slackening of the hoisting-rope being caused simply to initiate the movement.

We provide another automatic stop, which, through the same arresting and holding devices, stops the machinery when the drum and connected mechanism have turned to such extent as to bring the car to the top or bottom of its course.

Our automatic stops do not prevent the operating of the usual means for stopping and reversing at will in the ordinary working of the elevator.

The accompanying drawings form a part of this specification, and represent what we con-

sider the best means of carrying out the invention.

Figure 1 is a general side elevation. Fig. 2 is a corresponding plan view. Fig. 3 is an elevation of certain portions in a direction at right angles to Fig. 1. Fig. 4 is a similar view of certain other portions. Fig. 5 is a vertical section of a detail on a larger scale.

Similar letters of reference indicate corresponding parts in all the figures where they occur.

A indicates the fixed parts, certain portions being designated, when necessary, by additional marks, as A' A².

A' is the bed, and A² the stationary parts or casing of an engine having four single-acting cylinders. B is the rapidly-rotating shaft of this engine, and B' a large brake-wheel thereon.

C is a brake-strap fitting on the brake-wheel and attached at the points indicated to a lever. Both ends of the brake-strap are attached to a three-armed lever. Two of the arms are nearly at right angles to each other. One of these, a, carries a roller, e. The long arm c carries the weight d. The roller e rests against a cam, E², carried on the starting-shaft E of the elevator which latter is supported in fixed bearings, and is provided with a pulley, E', engaged with the small starting-rope F, which extends up and down through the elevator-car, and may be operated at any time by the attendant in the ordinary manner. The form of the cam E² is such that whenever the shaft E is turned from one extreme position to the other, either to lower or to hoist, it liberates the lever a while in the middle position, and allows the weight d to tilt the entire lever and apply the brake C to the brake-wheel. Thus the engine and the entire machinery is certain to be stopped and held when the shaft is turned into its central position.

We provide a stop to prevent ever turning the shaft E beyond a certain extent in the direction to lower the elevator. The extent should be sufficient to run the elevator down at a proper rate when it is empty. When full, it will descend a little too fast, but the speed cannot become very excessive.

S is the stop. It is a projection or offset in

the cam E^2 , arranged to strike fairly against the roller so soon as it has turned to the allowed extent. Such stop should not be made adjustable, because bad judgment, mistake, or accident might adjust it wrongly.

5 We provide means for automatically turning the shaft E under certain conditions with the same result. One of the conditions is the slackening of the hoisting rope.

10 G is the drum, turned slowly by gear operated by the engine in any ordinary or suitable manner.

H is the hoisting-rope.

15 E^3 is a cam or eccentric keyed or otherwise firmly set on the starting-shaft E . It is engaged in a yoke, L' , on the valve stem L , which connects to a steam-valve (not shown) adapted by its position being shifted to give steam to induce the engine to hoist or lower. The 20 parts are so adjusted that the turning of the starting-shaft E in one direction will move the rope, and consequently the valve-stem, in the direction to hoist, and turning the starting-shaft in the opposite direction will move the stem L in the direction to lower. Holding 25 the starting-shaft E in the intermediate position will hold the engine stopped.

30 There is liability, more especially in freight elevators, for the car to be temporarily arrested in its descent by the engagement of some article carried on it with one of the floors or with some other object. As ordinarily constructed, the rope H will continue to unwind under such conditions, and serious accidents 35 are liable to occur. We provide for automatically stopping the engine, the moment the rope is slackened, and we use the power of the engine to effect the necessary changes to attain this end.

40 I is a gear-wheel turning loosely on the starting-shaft E , and rotated with the motion of the drum G by means of a gear-wheel, J^2 , which is fixed on the shaft J , receiving motion through a gear-wheel, J' , from a gear-wheel, 45 G' , carried on the drum-shaft. (See Figs. 1 and 2.) One side of the wheel I , which thus turns constantly when the engine is running, is provided with an annular series of ratchet-teeth, I' .

50 K is a wide gear-wheel feathered on the starting-shaft E , and collared, as indicated by k . The side of this wheel presented toward the wheel I is provided with a corresponding annular ratchet, K' .

55 M^* is a grooved sheave turning loosely, and also free to move endwise, on a cylindrical bar, m' , lying parallel to the axis of the drum G . This bar is a portion of a rectangular frame, M , which turns on a fixed axis, m , below. 60 The arrangement is such that the gravity of the parts presses the sheave M^* gently against the hoisting-rope H .

P is a lever pivoted to the fixed framing at a point, p , and extending over a lateral projection, M^2 , on the frame M . There is a beveled offset, p' , on the under side of P , so arranged that when the rope H is slackened from

any cause the frame M falls inward toward the drum G . This allows the lever P to sink. Q is a connection from this lever to the lower 70 arm, R' , of a bell-crank lever turning on a fixed center, r , the upper arm, R^2 , of which engages by means of the collars k with the wide gear-wheel K , so as to slide it endwise on E . The sinking of the lever P when the frame M 75 moves toward the drum G engages the axially-sliding wide gear-wheel K with the constantly-revolving wheel I by means of their annular ratchets. A turning motion is thereby imparted by the power of the engine through the 80 wheel K to the starting-shaft E , and the machinery is promptly stopped.

To readjust the parts the attendant must operate the rope F and turn the starting-shaft E , so as to hoist. The annular ratchets on the 85 wheels K and I are beveled, so that this motion can be allowed. When, by the turning of the engine in the proper direction, the hoisting-rope F is again tightened, all the parts will be again restored to their original positions. The 90 offset p' and the corresponding face of the projection M^2 are sufficiently inclined to allow the restoration. After properly adjusting the freight on the car or otherwise removing the difficulty the starting-rope may be again operated to turn the shaft E and its connections into the position to lower, and the lowering 95 will be resumed and proceed successfully.

The parts described, with some additional mechanism, perform another important function—that of insuring the stoppage of the elevator-car at each end of its motion. This is particularly important at the upper end of its motion, as overwinding would produce a fatal accident. The ordinary automatic stop operating through the starting-rope F may fail through breakage or other accident to this long and slender rope. The stop to be described acts independently thereof. It is close to the engine.

100 J^3 is a disk fixed on the shaft J in the position represented. Between this and J^2 the shaft J is screw-threaded. A gear-wheel, N , is tapped to receive these screw-threads, and is fitted loosely thereon. Its teeth are engaged with the teeth of the wide gear-wheel K . Each face of the gear-wheel N is provided with projections N' , adapted to engage with corresponding projections on the adjacent faces of the wheels J^2 and J^3 . While the 105 elevator-car is running in either direction, this wheel N is traversed idly along on the shaft J without turning. As the car approaches either end of its course, the projections on the wheel N are brought into contact with the projections on the wheel J^2 or J^3 , causing the wheel N to commence to rotate. This motion will rotate the wide wheel K and turn the starting-shaft E , with the effect to 110 shut off steam and put on the brake, as before described. The brake-wheel B' is on the engine shaft B , which revolves rapidly. The proper stronger and slower motion is communicated therefrom to the drum by means of 115

an intermediate shaft, O, in the long-approved manner. The gear-wheel K should be sufficiently wide to allow the wheel N to traverse axially to the required extent while remaining in gear.

The brake should be put on gently. We provide means for insuring this, and for conveniently adjusting its rate. T is a hollow cylinder with its open end downward, and to having internal channels, t, extending up from its bottom rim nearly but not quite to the top. There is an orifice in its upper end controlled by a screw, T'. By turning this screw in one direction or the other the aperture for the escape of air is increased or diminished at pleasure. U is a piston having a piston-rod, U', the lower end of which is pivoted to a fixed point, u. The piston is hollow and provided with a self-acting valve, V, opening upward. 15 The piston is sufficiently long to afford a good bearing in the cylinder. The upper end of the cylinder being pivoted to the lever c, the latter arm will, when the frame M moves, descend rapidly until the brake-strap is 20 slightly tightened, and then descend slowly as the air imprisoned above the piston, after the tight part of the cylinder is presented thereto, shall flow out through the adjustable aperture controlled by T'. This puts on the brake 25 with any degree of moderation desired.

W is a turn-buckle, by turning which the length of the brake-strap C may be adjusted with any required degree of nicety. This should be adjusted so that on applying the 30 brake the gravity of the weight d will promptly depress the lever-arm c until the strap C shall be tightened, and so that just at this period the piston U will enter the portion of the cylinder T beyond the grooves, and the further 35 descent of the weight will be gradual, the rate depending on the amount of opening which may be provided by the adjustable screw T'.

Operation: Suppose the car to be at the bottom. The operator pulls the starting-rope F 40 and turns the shaft E in the direction to hoist. That act, by the operation of the cam E², tilts the lever a c and slackens the brake-strap C, setting the machinery free, and at the same time by the cam E³ moves the valve-stem L so 45 as to give steam to the engine. The several pistons, being acted upon in the proper succession, rotate the shaft B, and through the gearing shown give the proper slow rotation to the drum G and wind up the hoisting-rope H. 50 When the proper floor is reached, the operator pulls the rope F, to turn the shaft E in the opposite direction, until the roller e drops into the notch in the cam E², allowing the lever a c 55 to be tilted by the weight d and apply the brake-strap C to the wheel B'. The lever is liberated rapidly, but it turns slowly by reason of the resistance of the air in the cylinder T against the motion of the inclosed piston U, which is attached to the bed-plate. The same partial 60 turning of the shaft E, acting through the cam E³, moved the valve and cut off the supply of steam. During the period while the car re-

mains stopped it is held by the force of the brake C, in addition to other means. A fresh movement of the starting-rope to turn the shaft 70 E in the same direction will repeat the operation of hoisting, or a reverse movement will lower. In either case the brake will be taken off and the steam allowed to turn the shaft by the same partial turning of the starting-shaft 75 E. If from any cause the car is obstructed in lowering so that the hoisting-rope is slackened, the effect is instantly felt by the roller M*, which is carried on the frame M, and which, being no longer supported by the rope, tilts inward toward the drum G. As soon as it has moved in this direction a very short distance, the arm M² is transferred away from its bearing under the lever P, and is placed under the notch p', allowing the lever P to sink. This, 80 through the link Q and bell-crank lever R' R², gives an endwise movement to the long pinion K, causing it to clutch with the wheel I, which will cause K to turn, and thereby partially rotate the shaft E, on which it is feathered, turning it in the direction to shut off the supply 85 of steam and to put on the brake, with the same effect as when the operation is performed by the attendant. The parts are so adjusted that when the elevator-car has been run up to 90 the top floor, and before it touches the work above, the action of the screw-thread J will have traversed the gear-wheel N until it 95 clutches with the wheel J². So soon as this condition is attained, the wheel N will be 100 turned, and impart through the wheel K the proper turning motion to the shaft E to stop the machinery. When the car has run down to the lower floor, the wheel N will clutch with the wheel J², and induce the same partial turning 105 of the starting-shaft.

We attach importance to the fact that by our invention the power of the engine itself is applied to operate the valve-stem L and stop the engine. The weight or other force urging 110 the sheave M* against the rope H may be only sufficient to overcome the inertia and slight friction of the frame M. This motion is not resisted, and so soon as it has moved a little, to allow the lever P to drop and the wide 115 wheel K to be moved axially, the power of the engine engages and turns the latter, and effects the stoppage without imposing any tax on the frame M.

Modifications may be made in the forms and 120 proportions of the details without departing from the principle or sacrificing the advantages of the invention. We can, if preferred in any case, instead of applying the brake on the quickest shaft, arrange the brake-strap C to 125 apply on a suitable smooth wheel on the intermediate shaft, O, or on a suitably-prepared surface on the drum itself. We can dispense with the roller shown on the end of the lever a, and allow the cam E² to act directly on a 130 suitable smooth surface of the lever. The gearing by which the power of the engine is communicated to the drum may be varied within wide limits. We can use an endless

screw with worm-gear, or can dispense with the gearing altogether and connect a suitable engine directly to the drum. The sheave M^* need not be narrow and capable of traversing 5 endwise on the frame M . It may be wider even than full width of the drum. The effect will be the same.

We claim as our invention—

1. In an elevator, the reversing-wheel E' , 10 fixed on the reversing shaft E , and the cam E^2 , fixed on the same shaft, in combination with the brake-wheel B' and brake-strap C , and the connected levers a c , the arm c carrying weight d , and having its connection with the strap C 15 at a point between the fulcrum of the lever and the weight, all arranged for joint operation as set forth.
2. In an elevator, the sheave M^* and connected frame M , arranged to press gently 20 against the hoisting-rope H , in combination with means, as the arm M^2 , lever P , link Q , lever R' R^2 , wheel K , and reversing-shaft E , for engaging the power of the engine to shift the valve and apply the brake whenever the hoisting-rope slackens, as herein specified. 25
3. In an elevator, the reversing-pulley E'

and operating means F , for turning the reversing-shaft at will in any position of the elevator-car, in combination with the stopping mechanism, as the arm M^2 , lever P , link Q , 30 lever R' R^2 , and wheels K and I , for operating the reversing-shaft E automatically under certain conditions, and the engaging means, as the beveled ratchets I' and K' , arranged for joint operation as herein specified.

4. In an elevator, the brake-wheel B' , brake-strap C and means for applying it by a moving force, as the weight d , the piston U , and cylinder T t , combined and arranged for joint operation to effect the application of the brake 40 by a gradual movement, substantially as herein specified.

In testimony whereof we have hereunto set our hands, at Philadelphia, this 1st day of February, 1886, in the presence of two sub- 45 scribing witnesses.

DENNIS FRISBIE.

EDWARD M. LOCKWOOD.
